UNITED STATES PATENT OFFICE.

ROBERT H. AHLERS AND EARL M. POLK, OF DAYTON, OHIO, ASSIGNORS TO THE DAYTON ENGINEERING LABORATORIES COMPANY, OF DAYTON, OHIO, A CORPORATION OF OHIO.

APPARATUS FOR MAKING ARMATURES.

Application filed November 20, 1923. Serial No. 675,971.

To all whom it may concern:

Be it known that ROBERT H. AHLERS and EARL M. POLK, citizens of the United States of America, residing at Dayton, county of

Montgomery, State of Ohio, have invented certain new and useful Improvements in Apparatus for Making Armatures, of which the following is a full, clear, and exact description.

10 This invention relates to the manufacture of armatures for dynamo electric machines, and particularly to the type of armature having notched risers for receiving the leads of the armature conductors.

15 The objects of the invention include the mounting of a commutator having notched risers upon the armature shaft in correct location with respect to the armature conductor leads, and the moving of these leads into 20 the notches of their respective risers.

In order to accomplish this object one form of the invention includes a fixture for holding an armature with the commutator leads and one end of the armature shaft exposed and power means for driving a commutator having a hollow core or hub over the exposed end of the shaft, means for locating the conductor leads so they will project through the proper notches in the risers 25 of the commutator as the commutator is driven over the shaft.

Other and further objects of the present invention will be apparent from the following description, reference being had to the 30 accompanying drawings wherein one form of the present invention is clearly shown.

In the drawings:

Fig. 1 is a front elevation of one form of machine embodying the present invention.

40 Fig. 2 is a plan view thereof.

Fig. 3 is a sectional view on the line 3—3 of Fig. 1, certain parts being shown in positions differing from Fig. 1.

Fig. 4 is a fragmentary longitudinal sectional view on a scale larger than Figs. 1, 2 and 3, the section being taken on line 4—4 of Fig. 3.

Fig. 5 is a fragmentary sectional view on the same scale as Fig. 4, showing the commutator indexing bar, and the commutator in position corresponding to Fig. 1.

Fig. 6 is a view partly in plan and partly

in section of the armature holding fixture, showing certain parts in positions corresponding to Fig. 1, the section being taken 55 on line 6—6 of Fig. 1.

Figs. 7 and 8 are sectional views on the lines 7—7 and 8—8 of Fig. 4.

Fig. 9 is a fragmentary plan view of a block for guiding certain movable elements 60 shown in Figs. 7 and 8.

Referring to the drawings, 20 designates a base having supporting pedestals 21 and 22 connected with and supported with head 23. The head 23 provides a cylinder 24 and a 65 piston rod bearing 25 concentric with the cylinder for receiving a piston rod 26 attached to a piston 27. Except for the piston rod bearing 25 the cylinder 24 is closed at its lower end and the upper end is closed 70 by cover 28 attached by screws 29. The piston 27 is actuated by a compressed fluid such as air which is introduced in the usual manner upon the upper and lower sides of the piston by means of pipes 30 and 31 respectively connected with a supply pipe 32 by means of a valve 33 which selects passages providing communication between pipe 32 and either one of pipes 30 and 31.

The pedestal 22 supports collars 40 and 41 80 which may be mounted in any desired position of adjustment by means of set screws 42 and 43 respectively. Between the collars 40 and 41 there is located a hub 44 of bracket

45 which carries at its free end a bearing 46. The hub 44 is provided with a notch 47 for receiving a lug 48 extending from the collar 40. Thus the rotation of the bracket 45 is limited. The bearing 46 supports a

plunger 50 carrying adjacent its upper end a collar 51. A spring 52 is located between the bearing 46 and the collar 51 attached to the plunger 50 and tends to press the plunger upwardly toward a pressure block 53 attached by a set screw 54 to the piston rod 26. The plunger 50 is provided with a shoulder 55 and its lower end is provided with a central recess 56. (See Fig. 4.)

The apparatus for holding an armature and locating its windings preparatory to receiving the commutator includes a base block 60 attached to the base 20 by screw 61. The base block 60 is provided with a central recess 62 coaxial with the plunger 50. The

block 60 is adapted to receive one or more armature shaft supporting blocks 63, the size of which depends on the size of the armature to be operated upon. The block 5 63 is provided with a central bore 64 for receiving an armature shaft, the bore being coaxial with the plunger 50. Block 63 is provided with a shank 65 which is received by an aperture in block 60 which is also coaxial with plunger 50.

10 For the purpose of locating an armature core the block 60 is provided with a transverse radially extending bore 66 for receiving a pointed plunger 67 having a head 68. A spring 69 retained by plug 70 bears against the head of plunger 67.

15 For the purpose of guiding certain transversely and radially movable elements there is provided a guide block 71 which, referred 20 to Figs. 4 and 9, comprises a ring 72 and a plurality of spaced wedge shaped parts 73 which are integral with the ring 72. The spaces 74 between adjacent wedges 73 provide ways for guiding certain elements 25 to be described. This guide block has a central opening which is of the same diameter as the recess 62 and is coaxial therewith. The block 71 is attached to the block 60 by means of one or more screws 75. As 30 shown in Fig. 4, the wedge portions 73 are spaced from the block 60 to provide a space which is occupied by a camming ring 76 which is journalled on the exterior of the ring 72 of block 71. The camming ring 76 35 is provided with a circular row of inclined slots 77 and with an operating handle 78.

40 The guide block 71 supports a circular plate 80 having a flange 81 and a hub 82 which spaces the flange 81 from the upper 45 surface of the guide block 71. The plate 80 is attached by screws 83. The space between the block 71 and the flange 81 is occupied by a camming plate 84 which is journalled on the hub 82 and is provided with a circular row of inclined slots 85 and with an operating handle 86. Plate 84 carries a stud 87 having a reduced upper end 88.

50 The plate 80 supports a semi-cylindrical bracket 90 attached to the plate by screws 55 91. The inner wall 92 of the bracket 90 merges with a conical surface 93 of the plate 80. The bracket 90 carries a pin 94 providing a fulcrum for a semi-circular plate 95 provided with a semi-circular notch 96 for receiving the plunger 50 when the plate 95 is in the position shown in Figs. 3, 4 and 5. The plate 95 is actuated by handle 86 by means which includes two spaced leaf spring members 97 and 98 attached by screw 99 to an extension 100 provided on the plate 95. The springs 97 and 98 normally bear against opposite sides of the reduced end 88 of stud 87. Obviously the plate 95 is rotated by operating the handle 86.

65 Apparatus for indexing the commutator

which is assembled by means of this machine includes a pointed indexing slide 101, which slides in a notch provided in a boss 103 extending upwardly from the plate 80. The slide 101 is maintained in position by 70 means of a plate 104 having a slot 105 for receiving a handle 106 attached to the slide 101. The plate 104 is attached by screws 107 to the boss 103. The showing of this apparatus in Fig. 1 has been omitted for 75 sake of clearness.

80 During the assembly of the commutator upon the armature shaft, the bar conductors of the armature are clamped in position by apparatus which includes a plurality of 85 slides 110, each of which slides through one of the spaces or notches 74 provided in the guide plate 71. Each slide 110 is provided with an inclined end surface 111 formed according to the inclination to the vertical 90 of the armature conductors. Each slide is provided with a stud 112 received by one of the inclined camming grooves 77 of plate 76. Referring to Figs. 4, 6, 7 and 8, rotation of the handle 78 clockwise will cause the slides 110 to move from the position shown in Fig. 6 to the position shown in Fig. 8.

95 The apparatus for locating the ends of the armature conductors correctly preparatory to receiving the commutator includes a plurality of radially movable slides 115 which move in the notches 74. Each slide 115 is provided with inwardly projecting fingers 116 and 117 (see Fig. 7) and each slide carries a stud 118 received by one of the notches 85 of the plate 84. Rotation of the handle 86 counter-clockwise will cause the slides 115 to move radially inwardly for the purpose of locating the ends of the armature as will be explained more fully hereinafter.

Mode of operation.

100 The machine operates upon an armature 110 120 having a slotted core 121 mounted on a shaft 122. The machine is conditioned as shown in Figs. 1 and 6. The armature is located in recess 62 with the lower end 115 of shaft 122 received by block 63. Block 63 is interchangeable with other blocks of varying dimensions so that the shoulder 123 (see Fig. 4) of the shaft 122 will be located the proper distance from the bottom 120 of recess 62 in order to locate armatures of different dimensions properly with respect to the fixture. The armature 120 is turned so that the spring pressed pin 67 is received by one of the core slots 124. The armature is now located so that the upper 125 end of shaft 122 is exposed and the ends of the armature conductors ready to be accurately located so as to receive the commutator. Each conductor lead includes a straight portion substantially parallel with 130

the shaft and angularly offset with respect to the core slot receiving the conductor. Upon reference to Figs. 4, 5 and 6, it will be seen that the ends of the conductors are located approximately in two concentric circular rows 125 and 126 and the ends in one row are substantially radially aligned respectively with the ends in the other row. In other words, the conductors' ends are located in pairs which are substantially in alignment.

A commutator 127 having connected with each commutator bar bendable riser portions 128 and 129 which define notches for receiving respectively the pairs of conductor ends, is manually located upon the upper end of shaft 122 as shown in Figs. 1 and 6. The commutator is angularly adjusted so that the index slide 101 points to one of the insulating segments between the commutator bars.

Then the handles 78 and 86 are moved from the position shown in Figs. 1 and 6 to the positions shown in Figs. 2 and 4 to cause the slides 110 and 115 to move toward the armature into the positions shown in Fig. 4 and in Figs. 7 and 8 respectively. As the slides 115 move inwardly each one engages a pair of conductor ends 125 and 126 and causes them to be moved radially inwardly and to be located in correct angular position so as to be received by the proper commutator riser. The conductor ends are now located so that the commutator may be driven over the shaft.

The movement of handle 86 from the position shown in Fig. 6 to that shown in Figs. 3 and 4 will cause the plate 95 to be rotated into the position shown in these figures, the notch 96 being aligned with the plunger 50. By operating valve 33, fluid pressure is admitted to the upper end of cylinder and the plunger 50 will descend until the shoulder 55 strikes the upper surface of plate 95 which limits further downward movement of the plunger. The operation causes the commutator to be driven over the shaft as far as shown in Fig. 4. The conductor ends have been entered between the risers.

While the fluid pressure is turned off the handle 86 is returned to the position shown in Fig. 6, to retract the locating slides 115 and the plate 95, while the slides 110 remain in position shown in Fig. 8, to prevent any of the conductor leads being pulled away from the commutator in case a lead should stick to a slide 110. This operation removes the bars 115 from the path of movement of the commutator and the path 95 from the path of movement of the plunger shoulder 55. Then the handle 78 can be returned to the position shown in Fig. 6 to retract the stripper slides 110.

Fluid pressure is admitted upon the up-

per side of piston 27 to cause it to move downwardly until stopped by the cylinder. This operation will cause the commutator 127 to be forced down the shaft 122 to the desired distance from the core 121.

Fluid pressure is then admitted upon the underside of the piston 27 to permit the plunger 50 to be raised by spring 52 to the position shown in Fig. 1. The armature is removed and the apparatus is ready for a subsequent operation. By an operation of bending the riser tangs 128 and 129 over the pair of conductor ends, the conductors are connected with their respective commutators.

In case it is desired to remove parts mounted on block 60, the bracket 45 can be rotated out of alignment therewith. In the condition of the machine as shown in Fig. 1, the ends of the plunger 50 are free of the plate 95 and the pressure block 53.

While the form of embodiment of the invention as herein disclosed constitutes a preferred form, it is to be understood that other forms might be adopted, all coming within the scope of the claims which follow.

What is claimed is as follows:

1. Apparatus for manufacturing armatures having conductor leads extending from the core and received by notched risers of the commutator, comprising in combination, means for holding an armature core with conductor leads extending therefrom, means for locating said leads so that they may be received by the commutator risers, and means for moving a commutator endwise along the armature shaft so that the commutator risers will receive all of the conductor leads simultaneously.

2. Apparatus for manufacturing armatures having conductor leads extending from the core and received by notched risers of the commutator, comprising, in combination, means for holding an armature core with conductor leads extending therefrom, means for engaging the leads to move them toward the armature shaft and for properly spacing the leads, and means for moving a commutator endwise along the armature shaft so that the commutator risers will receive all of the conductor leads simultaneously.

3. Apparatus for manufacturing armatures having conductor leads extending from the core and received by notched risers of the commutator, comprising, in combination, means for holding an armature core with conductor leads extending therefrom, notched members movable toward the armature shaft for engaging the leads to move them toward the armature shaft, means for preventing the leads moving away from the shaft when said notched members recede from the shaft, and means for moving a commutator endwise along the armature

shaft so that the commutator risers will receive all of the conductor leads simultaneously.

4. Apparatus for manufacturing armatures having conductor leads extending from the core and received by notched risers of the commutator; comprising, in combination, means for holding an armature core with conductor leads extending therefrom, notched members movable toward an armature for engaging the leads to move them toward the armature shaft, means for preventing the leads moving away from the shaft when said notched members recede from the shaft.

5. Apparatus for manufacturing armatures having conductor leads extending from the core and received by notched risers of the commutator, comprising, in combination, means for holding the armature core with conductor leads extending therefrom, devices for engaging the leads to move them toward the armature shaft and for properly spacing the leads, means for moving a commutator endwise along the armature shaft so that the commutator risers will receive all of the conductor leads simultaneously, a stop for limiting the operation of the commutator moving means when the leads are engaged by said devices, and means for retracting said devices and said stop.

6. Apparatus for manufacturing armatures having conductor leads extending from the core and received by notched risers of the commutator, comprising, in combination, a fixture for supporting an armature, means for moving a commutator along the armature shaft toward the conductors, a plurality of bars adapted to move toward the conductors and to locate them properly in order to be received by the risers of the commutator, and means for moving all

of the bars simultaneously toward the conductors.

7. Apparatus for manufacturing armatures having conductor leads extending from the core and received by notched risers of the commutator, comprising in combination, a fixture for supporting an armature, means for moving a commutator along the armature shaft toward the conductors, a plurality of bars adapted to move toward the conductors and to locate them properly in order to be received by the risers of the commutator, a stop for limiting the operation of the commutator moving means, and means for moving the stop into operative position and all of the bars simultaneously toward the conductors and for retracting said stop means and bars.

8. Apparatus for manufacturing armatures having conductor leads extending from the core and received by notched risers of the commutator comprising, in combination, a fixture for supporting an armature, means for moving a commutator along the armature shaft toward the conductors, a plurality of bars adapted to move toward the conductors and each having a notch adapted to receive certain armature conductor leads in order to locate them properly to be received by a certain riser, means for advancing and retracting the bars simultaneously, a second set of bars located adjacent the first mentioned bars and each movable into contact with an armature conductor lead, in order to retain it in position while the locating bar is being retracted, and means for advancing and retracting the second set of bars.

In testimony whereof we hereto affix our signatures.

ROBERT H. AHLERS.
EARL M. POLK.
